UNITED STATES PATENT OFFICE.

CLAUDE A. LEWIS, OF HOUSTON, TEXAS, ASSIGNEE TO AMERICAN WINDOW COMPANY,
A CORPORATION OF DELAWARE.

WINDOW.

Application filed September 7, 1926, Serial No. 133,930.

My invention relates to windows, and has particular reference to windows in which the lower sash is slideable but in which the upper sash is opened by swinging the upper end 5 inwardly into the room.

It is an object of the invention to provide in a window of this construction a casing in which the inner side has a practically straight or plane surface provided with 10 channels to receive the lower sash.

It is also an object to construct the casing so as to enclose the channel in which the sash cords operate in connection with the lower sash and to thus maintain a tight 15 closure at each side of the upper sash when tilted inwardly to provide a vent.

It is also an object to fit the sash within the casing so as to maintain the same in weather-tight contact with the casing.

20 Referring to the drawing herewith, Fig. 1 is a vertical section through a window casing showing the window sash removed. Fig. 2 is a transverse section on the plane 2-2 of Fig. 1, showing the upper sash in position in the frame. Fig. 3 is a similar section on the line 3-3 of Fig. 1, showing the lower sash in position. Fig. 4 is a detail of a slightly different embodiment of the 25 window jamb. Fig. 5 is a view similar to Fig. 2 but illustrating a sheet metal construction of window casing. Fig. 6 is a view similar to Fig. 3 of a sheet metal embodiment of the invention. Like numerals of reference are employed to designate like 30 parts in all the views.

In constructing my improved form of window, I contemplate forming a window jamb illustrated at 1 of either wood or sheet metal, and in Figs. 1 to 4 inclusive, I have 35 shown the window jamb as made up of a plate of wood having on its inner side a channel 2 therein of sufficient depth to receive the rider 9 for the lower sash. Adjacent the outer side of the plate 1 is a longitudinal groove or channel 4 which is adapted 40 to form a rain pocket, as will be later described. Outside the plate 1 is a vertical stop member 5 projecting toward the window opening beyond the jamb to form a contact 45 for the outer face of the upper sash. There are the side casement members 6 and 7, as in the usual construction.

The lower sash 8 is mounted upon a rider 9 to which it is pivotally connected by pins 50 10. The rider 9 is preferably formed of

sheet metal bent into U-shape, the open side being presented toward the outside of the window. The inner side of the rider has engagement with a sash cord 11 to which a sash weight 12 may be connected. The sash 60 cord 11 extends upwardly from the lower sash and may be passed over a pulley 13 in the usual manner.

I have contemplated closing the channel 2 in front of the upper sash so as to hide the 65 sash cord and also to present a plane continuous surface for contact with the side of the upper sash when it is moved. This closure is formed by a sheet metal plate 14 secured by wood screws 15 to the window jamb 70 on the outer side of said channel and extending forwardly to nearly close the channel, allowing however the slot or opening 16 through which the wall of the sheet metal 75 rider may pass, as shown in Fig. 2.

The upper sash 18 is mounted closely adjacent the stop member 5 at the outer side of the window jamb and is pivoted at its lower end to swing inwardly. For this purpose it has a plate indicated at 19, the forward 80 end of which is provided with an arm 20, the lower side of which is arcuate and fits within a supporting bracket 21 formed upon a plate 22 secured to the window jamb immediately to the rear of the lower sash. It 85 is contemplated that the upper sash may be swung inwardly at its upper end to provide a vent between the sash and the upper end of the casing, as indicated in Fig. 1. In this position of the upper sash the side of 90 said sash will fit closely against the window jamb and the plates 14 substantially covering the channel 2. In this position there will be no chance for the escape of rain or wind around the sides of the sash. A vent 95 may only be provided above the sash into the room. This will allow the vent to be left open in rain storms of ordinary intensity without danger of the rain finding access to the inner side of the window.

When the window is in closed position, as shown in Fig. 2, the sash makes close contact with the stop member 5, and if rain or wind passes the sash it will come within the rain pocket 4 and the rain may drain 100 downwardly by gravity and will not enter the room. In case of the lower sash the stop member 23 may be secured on the window jamb to the rear of the sash and a rain pocket is formed inside the stop member by 105 110

the rider 9, the open side of which faces outwardly.

In Fig. 4 the window jamb, shown in Fig. 3, is illustrated removed from the casing, the stop member 23' being formed as in the Fig. 3 embodiment, except that it is not set within the shallow groove in the window jamb, as shown in Fig. 3.

In Figs. 5 and 6 the formation of the window jamb is of sheet metal construction and the parts thereof are integral. The stop member 4' extends to the rear of the sash 18' and contact is made between the sash and the window along a line 24 on the outer side of the sash, and also at 25 with a laterally extending flange 26 upon the window casing. A rain pocket is formed at the outer side of the sash to allow drainage of rain or moisture which enters between the sash and casing at 24.

The lower sash is mounted upon a rider 9' which has one side adjacent the sash extended outwardly the full width of the sash and recurved at 27 to enclose the rearward side of a rain pocket 28. A vertical flange 29 is secured to the window jamb adjacent the outer edge of the lower sash to close the rearward end of the opening in the rider, as shown in Fig. 6. The inner face of the sash is also extended laterally past the edge of the rider at 30 so as to make a closer fit with the casing and also to hide the view of the rider from the forward side.

It will be noted in my present form of window casing that the same will be simple and economical to construct, and that the upper and lower sashes will fit within the casing in such manner that there will be no liability of leakage of rain or wind about the window sash while it is in closed position. The upper sash may be swung inwardly to provide a vent without allowing the rain and wind to find access around the sides thereof. The advantages of this construction will be apparent to those skilled in the art.

What I claim as new and desire to protect by Letters Patent is:

1. In a window a casing, including an upright jamb, the inner face thereof being plane except for a sash channel therein and a marginal groove, a lower sash, a rider on said sash slideable within said channel, a

plate of sheet metal approximately closing said channel at the upper portion thereof, and an upper sash fitting in said casing and adapted to swing inwardly across said plate.

2. In a window a casing, including an upright jamb, the inner face thereof having a sash channel therein and a marginal groove, a lower sash, a rider on said sash slideable within said channel, said rider being of sheet metal of channeled form with its open side presented outwardly, a plate of sheet metal projecting into the open side of said rider when the lower sash is raised and approximately closing said channel at the upper portion thereof, and an upper sash fitting in said casing and adapted to swing inwardly across said plate.

3. A window including a casing, jambs in said casing having channels longitudinally therein, riders in said channels, sash cord secured to said riders in said channels, a plate on said jamb overlapping said channels, and an upper sash fitting between said jambs and movable between said plates.

4. A window including upper and lower window sashes, jambs at each side of said sash, said jambs having a channel therein, riders of sheet metal on said lower sash slideable in said channels, said riders having their outer sides open and a stop member on said jambs at the outer side of said lower sash adapted to close the outer side of said rider, said rider forming an air pocket in the manner described.

5. In a window a window jamb having its inner side a plane surface except for a channel therein and a marginal groove at its outer edge, sash riders slideable in said channel, and a plate overlapping the upper portion of said channel and adapted to project into the said riders in the manner described.

6. In a window, a window jamb, upper and lower sashes mounted therein, the jambs inside said upper sash being plane except for channels therein, a lower sash, riders thereon slideable in said channels, said upper sash fitting closely against said jamb and pivoted at its lower end to swing therein.

In testimony whereof I hereunto affix my signature this 2d day of September, A. D. 1926.

CLAUDE A. LEWIS.
